OIL SAND BIT

Filed Feb. 2, 1931

FIG. 1

FIG. 2

WILLIAM O. SCOTT

INVENTOR

Paul W. Freeman
ATTORNEY

UNITED STATES PATENT OFFICE

WILLIAM O. SCOTT, OF WALNUT PARK, CALIFORNIA

OIL SAND BIT

Application filed February 2, 1931. Serial No. 512,950.

The object of my invention is to provide a tool adapted to drill a hole of enlarged diameter when drilling in soft formation, as when drilling through oil sand.

5 My improved bit is adapted to be inserted inside a string of casing, at the end of a drill string, and thus lowered to the bottom of the hole. When the blades rest on the bottom they are automatically spread apart, 10 forming a fish tail bit of greater width than the diameter of the casing, while the lifting of the drill string causes the blades to fold up so that the bit may be withdrawn.

In the attached drawings, Fig. 1 shows the 15 complete bit in face elevation and Fig. 2 in edge elevation, as referred to the position of the blades,

And Fig. 3 is a section through the body on the line A—A of Fig. 1.

20 Referring to the drawings, 10 is a body adapted to fit within the size casing for which the bit is intended, this body having a standard threaded pin 11 and water channels 12. From this body a stem 13 having 25 the section shown in Fig. 3 extends downwardly, sliding within a similarly shaped opening formed within a collar 14 which is integral with the upper end of the blade body 15.

30 Each side of the blade body is slotted for a portion of its length as at 16 and within these slots center blocks 17—17 are attached to the sliding stem 13, the engagement of these blocks with the ends of the slots limiting the sliding movement of the shaft within 35 the body.

The lower portion of the body is slotted as at 18 for a portion of its length and within this slot are mounted the two blades 40 20a—20b, pivoted on a pin 21. The upper end of these blades above the pin, has each a projection 22a—22b of which one face is curved as at 23a—23b. These two projections or lugs lie face to face within the slot 45 as shown in Fig. 2.

The lower end of stem 13 is relieved on each side for half of its thickness, forming opposed projecting lugs 24a—24b having their lower or inner surfaces curved as indicated at 25a—25b.

When the bit is suspended from the drill pipe the device assumes the position shown in Fig. 1, in which the blocks 17 are at the upper ends of slots 16 and the lugs 24 are out of contact with lugs 22. In such position the blades are retracted and will pass inside the casing.

When the blades come into contact with the bottom of the hole the body 15 is lifted upwardly as regards the stem 13 and the curved surfaces 25 of lugs 24 are caused to slide over the curved surfaces 23 of lugs 22, thus forcing the upper ends of the blades inwardly and the lower ends of the blades outwardly. The spread of the blades will obviously be limited by the curvature and the relative travel of these two surfaces.

On lifting the drill string the stem is raised until blocks 17 contact with the upper ends of slots 16, thus lifting the body 15 and permitting the blades to fold into retracted position as their upper edges encounter the casing shoe.

I claim as my invention:

1. An expansion bit having a slotted body and a stem sliding therein, said stem being adapted for attachment to a drill pipe; two blades pivotally mounted within said slotted body, and cooperating lugs on the lower end of said stem and the upper ends of said blades adapted to force the lower ends of said blades apart as said stem is caused to move downwardly within said body by the vertically exerted pressure of the material to be drilled.

2. An expansion bit having a slotted body and blades pivotally mounted in said slot; an unthreaded stem slidably mounted within said body, and means whereby a downward movement of said stem in said body causes the stem to cooperate with the upper ends of said blades and the lower ends of said blades to diverge, said movement being made possible by the pressure of the material to be drilled upon the lower end of said slotted body.

3. In a bit of the class described, a slotted body and a stem adapted to slide therein to a limited extent, said stem bearing upon its top portion means for attachment to a

drill pipe and water supply channels, the slotted body having pivoted in its lower end two blades pivotally mounted within the body so that the cutting edges project out from the lower part of said body, said blades being provided with lugs above the pivot, shaped so as to stand apart when the cutters are hanging free, to engage the stem said lugs having bearing surfaces shaped so as to render them capable of being spread apart by the engagement of the said stem and when spread, to force the cutters into a position in which they can cut a hole of larger diameter than the slotted body, the position of the lugs when the cutters are in cutting position operating to limit the downward travel of the stem.

In witness that I claim the foregoing I have hereunto subscribed by name this 29th day of September, 1930.

WILLIAM O. SCOTT.
